UTILITY BRUSH

John W. Kaye, San Antonio, Tex.

Application November 6, 1950, Serial No. 12,862

Term of patent 14 years

(Cl. D9—2)

To all whom it may concern:

Be it known that I, John W. Kaye, a citizen of the United States of America, residing at San Antonio, Bexar County, State of Texas, have invented a new, original, and ornamental Design for Utility Brushes, of which the following is a specification, reference being had to the accompanying drawing, forming a part hereof.

Fig. 1 is a perspective view of a utility brush, showing my new design,

Fig. 2 is a side elevational view of the brush,

Fig. 3 is a front elevational view of the brush in a closed position,

Fig. 4 is a top plan view of the brush,

Fig. 5 is an underside plan view of the brush, and

Fig. 6 is a rear elevational view of the brush.

I claim:

The ornamental design for a utility brush, as shown.

JOHN W. KAYE.
